CLAIM

The ornamental design for a retaining wall block, as shown and described.

DESCRIPTION

FIG. 1 is a front perspective view of a first embodiment of a first retaining wall block of the present invention.

FIG. 2 is a side view, as taken from the left side of the retaining wall block of FIG. 1.

FIG. 3 is a side view, as taken from the right side of the retaining wall block of FIG. 1.

FIG. 4 is a first end view of the retaining wall block of FIG. 1.

FIG. 5 is a second end view of the retaining wall block of FIG. 1.

FIG. 6 is a top plan view of the retaining wall block of FIG. 1.

FIG. 7 is a bottom plan view of the retaining wall block of FIG. 1.

FIG. 8 is a front perspective view of a second embodiment of the first retaining wall block of the present invention.

FIG. 9 is a side view, as taken from the left side of the retaining wall block of FIG. 8.

FIG. 10 is a side view, as taken from the right side of the retaining wall block of FIG. 8.

FIG. 11 is a first end view of the retaining wall block of FIG. 8.

FIG. 12 is a second end view of the retaining wall block of FIG. 8.

FIG. 13 is a top plan view of the retaining wall block of FIG. 8; and,

FIG. 14 is a bottom plan view of the retaining wall block of FIG. 8.
